CLAIM

The ornamental design for a snowboard, as shown and described.

DESCRIPTION

FIG. 1 is a top, front left perspective view of a snowboard according to the first embodiment of my invention.

FIG. 2 is a top plan view of the snowboard of FIG. 1.

FIG. 3 is a rear, elevation view of the snowboard of FIG. 1.

FIG. 4 is a top, rear right perspective view of the snowboard of FIG. 1.

FIG. 5 is a bottom plan view of the snowboard of FIG. 1.

FIG. 6 is a front, elevation view of the snowboard of FIG. 1.

FIG. 7 is a left side, elevation view of the snowboard of FIG. 1, the right side, elevation view being a mirror image thereof.

FIG. 8 is a top, front left perspective view of a snowboard according to the second embodiment of my new invention.

FIG. 9 is a top plan view of the snowboard of FIG. 8.

FIG. 10 is a rear, elevation view of the snowboard of FIG. 8.

FIG. 11 is a top, rear right perspective view of the snowboard of FIG. 8.

FIG. 12 is a bottom plan view of the snowboard of FIG. 8.

FIG. 13 is a front, elevation view of the snowboard of FIG. 8; and,

FIG. 14 is a left side, elevation view of the snowboard of FIG. 8, the right side, elevation view being a mirror image thereof.

The broken lines in the drawing are for illustrative purposes only and form no part of the claimed design.
